(57) **CLAIM**

The ornamental design for display screen with graphical user interface as shown and described.

DESCRIPTION

1. Display screen with graphical user interface

1.0 : Front

FIG. 1.0 is a front view of a display screen with graphical user interface showing a racing car in a front perspective view during preparation for a race or during selection before race or during similar activities.

The broken lines defining the outermost periphery show the display screen and are not part of the claimed design. The remaining broken lines shown are for the purpose of illustration.

(Continued)

trating portions of the display screen with graphical user interface that form no part of the claimed design.
